Primary Examiner — Barbara Fox*Assistant Examiner* — Mehri F Bajoul(74) *Attorney, Agent, or Firm* — Ellen M. Bierman; Mark P. Walters; Lowe Graham Jones PLLC(57) **CLAIM**

The ornamental design for a packaging for plant material, as shown and described.

DESCRIPTION

FIG. 1 is a front plan view of a packaging for plant material showing my new design.

FIG. 2 is a rear plan view thereof.

FIG. 3 is a left plan view thereof.

FIG. 4 is a right plan view thereof.

FIG. 5 is a top front isometric view thereof; and,

FIG. 6 is a bottom front isometric view thereof.

The broken lines in the drawings depict portions of the packaging for plant material that form no part of the claimed design.

1 Claim, 6 Drawing Sheets(56)
